UNITED STATES PATENT OFFICE.

ELBRIDGE J. STEELE, OF NEW HAVEN, CONNECTICUT, ASSIGNOR TO
SARGENT & CO., OF SAME PLACE.

DESIGN FOR DOOR-HINGE.

Specification forming part of Design No. 7,245, dated March 17, 1874; application filed February 18, 1874.
[Term of Patent 7 years.]

To all whom it may concern:

Be it known that I, ELBRIDGE J. STEELE, of New Haven, in the county of New Haven and State of Connecticut, have invented a new Design for Door-Hinge; and I do hereby declare the following, when taken in connection with the accompanying drawings and the letters of reference marked thereon, to be a full, clear, and exact description of the same, and which said drawings constitute part of this specification, and represent, in—

Figure 1, a front view of one leaf; Fig. 2, a rear view of the other leaf.

This invention relates to a design for hinges for doors, commonly called "butt-hinges;" and the design consists in the ornamentation of the faces of the leaves and the form of the tips, as shown in the accompanying illustration, and hereinafter described.

First, the border around the edge of each leaf is of "Grecian-key" pattern in relief, and inside a plain edge, as shown in Fig. 1. Second, the panel or space within the border. The

A.

edge of the panel is composed of lines parallel, the sides straight, the ends semicircular, the center a combination of Grecian-key work, as shown in Fig. 1. Third, the rear face is a sunken panel, ornamented with Grecian-key work center and tracery therefrom toward each end, as shown in Fig. 2. The tip extending from the pintle contracts to a neck, then suddenly enlarges to the body of pyramidal form, and terminates in a conical tip.

I claim as my invention—

1. The design for border for hinge, as shown and described.
2. The design for panel of hinge, as shown and described.
3. The design for the rear face of hinge, as shown and described.
4. The design for tip of hinge, as shown and described.

ELBRIDGE J. STEELE.
